UNITED STATES PATENT OFFICE.

LOREN O. CRENSHAW, OF LOS ANGELES, CALIFORNIA, ASSIGNOR TO MAGNETIC SIGNAL COMPANY, A CORPORATION OF CALIFORNIA.

MOTOR COMPRISING A SINGLE COIL.

1,361,229.

Specification of Letters Patent.

Patented Dec. 7, 1920.

Application filed May 7, 1919. Serial No. 295,797.

To all whom it may concern:

Be it known that I, LOREN O. CRENSHAW, a citizen of the United States, residing at Los Angeles, county of Los Angeles, and 5 State of California, have invented a new and useful Improvement in Motors Comprising Single Coils, of which the following is a specification.

My invention relates to signals which are 10 especially adapted to be placed at railway crossings to warn traffic on the highway of the approach of trains on the railway. It may, of course, be used for other purposes and in other situations.

15 The principal object of my invention is to provide a signal of great simplicity having a very small number of parts and which will therefore be very reliable.

Referring to the drawings, which are for 20 illustrative purposes only,

Figure 1 is a cross section through the embodiment of my invention.

Fig. 2 is a section on a plane indicated by line 2—2 of Fig. 1.

25 Fig. 3 is a diagram of connections.

In the form of signal illustrated, a case 11 is provided, having a door 12 suitably secured in the side thereof. A shaft 13 turns freely in bearings 14 formed in the 30 case 11 and projects outside of the case as shown at 15 having a hub 16 rigidly secured thereon; a rod 17 secured in the upper portion of hub 16 carries a display 18 which may consist of a target painted any desirable color—red being preferred. Secured to the lower portion of hub 16 is a rod 19 carrying a pendulum 20, this pendulum being of sufficient weight to hold the parts in their vertical position as shown in Fig. 1, 35 when the signal is not operating. Rigidly secured to the shaft 13 are a pair of castings 25 to which an armature is secured. Secured in the top of the case 11 is a magnet 27 having an energizing coil 28 wound thereon, the 40 magnet and the armature being so located that they stand in the position shown in Fig. 1 whenever the signal is not in action. Secured to suitable insulation 30 on one of the castings 25 is a movable contact 31 which 45

is connected through a wire 32 with one terminal of coil 28, the other terminal of which is connected to a wire 33, which passes through a bushing 34 in the bottom of the case 11 to an external circuit. Secured by insulation 40 on the case 11 is a 50

casting 41 carrying a pin 42 on which a contact finger 43 is pivoted, this finger being provided with a torsion spring 44 which tends to rotate it in a counter-clockwise direction and hold it in electrical contact with 60 the movable contact 31. The amount of this rotation is, however, limited by a set screw 45. The stationary contact finger 43 is connected through a wire 46 with an external circuit which may contain a battery 47 or 65 other source of power contact making device 48, which may be actuated in any manner—in the case of a railway signal the contact device 48 is closed by the approach of a train to the crossing. 70

The method of operation of my invention is as follows:

The parts being in position shown in Fig. 1, the contact making device 48 is closed, thus closing the circuit through the stationary contact finger 43 to the movable contact 31, from thence through coil 28 and the wire 33 to the other side of the battery 47. The coil 28 is thus energized and tends to pull the armature 26 to the left as viewed 80 in Fig. 1. As soon as the armature is moved a short distance to the left, the set screw 45 strikes upon the casting 41 thus stopping the movement of the contact finger 43 which therefore breaks its contact with the movable contact 31, opening the circuit of the coil 28 and deenergizing the magnet 27. The pendulum 20 being in motion at the time the circuit is opened, swings some distance to the left, finally coming to rest at 90 some position with the pendulum 20 to the right of the vertical line of Fig. 1 and the display 18 to the left. The pendulum then swings back toward the right swinging the movable contact 31 against the stationary 95 contact finger 43 and moving the end of the finger 43 to the right for a short distance during which the coil 28 is again energized, pulling upon and tending to arrest the movement of the armature 26. The momentum given to the armature in its initial movement to the left is first neutralized or compensated for and as soon as it is brought to rest a second impetus is given, again pulling the armature to the left and thus producing a somewhat greater amplitude of swing than the initial swing; this increase in amplitude increases until the entire impetus is absorbed by friction and the signal 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 shown in Fig. 1, this oscillation continuing until the circuit is broken through the contact moving device 48, after which the signal settles into its original position so that 5 the signal will be in position to repeat its movement whenever the contact movement device 48 is again closed.

It will be noted that by using only one coil and one pair of contacts a very simple 10 form of signal is produced.

I claim as my invention:

A motor comprising a pendulum, a shaft from which said pendulum is dependent, an armature secured to said shaft, a magnet 15 having two limbs located in magnetic relationship to said armature, said magnet being so placed that it is in a position to at-

tract said armature when said pendulum is in its lowest position, a coil on one of said limbs, a movable contact secured to but insulated from said armature but connected to energize said coil, a contact finger pivoted on a fixed shaft and so placed as to make contact with said movable contact when the pendulum is in its lowest position, 20 and means for causing said contact finger to open the circuit with the said contact as said armature approaches its position in the maximum pull.

In testimony whereof I have hereunto set 30 my hand at Los Angeles, California, this 1st day of May, 1919.

LOREN O. CRENSHAW.
